Primary Examiner — Michelle E. Wilson*Assistant Examiner* — Sanjeev Paul(57) **CLAIM**

The ornamental design for a memory foam pillow, as shown and described.

DESCRIPTION

FIG. 1 is a left side view of a memory foam pillow showing my new design;

FIG. 2 is a right side view thereof;

FIG. 3 is a first perspective view thereof;

FIG. 4 is a second perspective view thereof;

FIG. 5 is a third perspective view thereof;

FIG. 6 is a fourth perspective view thereof;

FIG. 7 is a fifth perspective view thereof;

FIG. 8 is a sixth perspective view thereof;

FIG. 9 is a seventh perspective view thereof;

FIG. 10 is an eighth perspective view thereof; and,

FIG. 11 is a ninth perspective view thereof.

1 Claim, 11 Drawing Sheets---
